CONTAINER FOR TENNIS BALLS

Robert S. Feinberg, 81 Edgemont Place, Teaneck, N.J.
07666, and David A. Selick, 76 Le Roy St., Tenafly,
N.J. 07670

Filed Aug. 16, 1974, Ser. No. 497,899

Term of patent 14 years

Int. Cl. D3—02

U.S. Cl. D87—1 R

FIG. 1 is a top perspective view of a container for tennis balls showing our new design;

FIG. 2 is a side elevational view thereof; and

FIG. 3 is a bottom plan view.

We claim:

The ornamental design for a container for tennis balls, as shown and described.
